ADDRESSING AND TABULATING MACHINE

Harmon P. Elliott, Watertown, Mass.

Application September 14, 1935, Serial No. 40,609

34 Claims. (Cl. 101—58)

This invention relates to addressing and tabulating machines and especially wherein the addresses and the data to be printed or tabulated is contained in a series of printing plates or devices as stencils.

For certain classes of work as, for instance, the addressing of pension checks, the stencil in addition to containing the address carries a form which can be perforated in parts corresponding to the year, month, the contract number, the amount paid out or other desirable information pertaining to the address. The form, for instance, may consist of a series of horizontal lines of numbers running from zero to nine, each line containing repetitions of the same number and different lines containing different numbers, the numbers in the horizontal lines being arranged in vertical registration. The stencil is adapted to be perforated at selected numbers on selected lines that provide the desired information pertaining to the address of the stencil. Heretofore, it has been necessary to run the stencils from which addresses are taken through a tabulating machine to record the information indicated by the perforations of the stencils.

It is an object of the present invention to provide a printing machine wherein the tabulating mechanism is a part of the addressing machine and the information indicated by the perforations of the stencil can be recorded while the stencil is in the addressing machine and preferably while it is in addressing position so that the address and the information provided by the perforations can be recorded simultaneously.

A further object of the invention is the provision of an addressing machine having tabulating mechanism which is automatically set by the perforations or the equivalent of the stencil or printing device to record the information indicated by the perforations.

A yet further object of the invention is the provision of a printing machine having a plurality of tabulating type bars the positions of which are controlled by the perforations of the stencils when they are in a predetermined position, as the printing position, so that a record of certain type characters on said bars selected by the stencil can be recorded at the time the address of the stencil is being recorded, the type bars being automatically reset into a normal position following each printing operation.

A yet further object is generally to improve the construction of addressing and tabulating machines.

Fig. 1 is a plan view of an addressing and tabu-

lating machine embodying the present invention.

Fig. 2 is an end elevation looking at the left hand end of the machine of Fig. 1.

Fig. 3 is a front elevation of the machine of Fig. 1.

Fig. 4 is a sectional elevation taken transversely through the printing position of the machine of Fig. 1.

Fig. 5 is a sectional detail taken along line 5—5 of Fig. 4 and illustrating particularly the lower 10 sheet feeding rolls.

Fig. 6 is a perspective detail of the disabling mechanism for the sheet feeding rolls.

Fig. 7 is a detail plan view of the tabulating mechanism with the printing head removed.

Fig. 8 is a sectional detail taken along line 8—8 of Fig. 7.

Fig. 9 is a sectional detail taken along line 9—9 of Fig. 8.

Fig. 10 is a perspective view of a type bar of 20 the tabulating mechanism.

Fig. 11 is a perspective view of the type bar resetting device of Fig. 8.

Fig. 12 is a sectional detail taken along line 12—12 of Fig. 3 and illustrating particularly the 25 operating mechanism for the tabulating printing head.

Fig. 13 is a detail illustrating a portion of the printed record made by the machine.

Fig. 14 is a plan view of a stencil used with the 30 machine.

The address and data bearing printing device especially adapted for use in connection with the present invention comprises a stencil consisting of a generally rectangular stiff paper board frame 35 20, see Fig. 14, having in the upper portion a window 22 occupied by the usual stencil sheet bearing an address 24. The stencil frame 20 under the window is provided with a series of horizontal lines 26 of numbers, each horizontal line containing repetitions of the same number and different 40 lines containing different numbers. There can be, for instance, ten horizontal lines containing consecutive numbers from zero to nine. The numbers contained in the horizontal lines are arranged in vertical alignment and there may be as many vertical lines 27 of numbers as may be desired, each vertical line containing a consecutive series of numbers from zero to nine.

The machine herein illustrated is adapted to 50 cooperate with stencils having forty or less vertical lines of numbers, this being sufficient for the present purpose. The stencil is adapted to be perforated as indicated by the perforations 28 at selected numbers in selected vertical lines, the 55

numbers and lines selected being such as to indicate the desired information. The perforations operate to control a tabulating mechanism to effect the printing, in a single line, of the numbers indicated by the perforations, the spacing of printed numbers corresponding to the spacing between the vertical perforated lines.

The printing and tabulating machine embodying the present invention and operating upon a series of the above described stencils comprises a table or bed 30 supported on top of a suitable frame 32. A pair of horizontally spaced stencil supporting rails 34 constituting a stencil track or guideway are disposed above the table 30 and extend lengthwise of the table from the right to the left hand end thereof. A stencil holder 36 is disposed above the stencil track at one end thereof and is adapted to contain a pile of superimposed stencils. A pusher 38 is reciprocable lengthwise of the track and is arranged to move the successive lowermost stencils of the holder out of the holder and into and along the track, the stencils being finally deposited in a stencil receiver 40 located at and mainly below the other end of the table and track.

Whereas in the usual stencil printing machine the inked printing roll and the inking mechanism are located above the table and the anvil or platen is located below the table, in the present machine the relation of the parts is reversed because of the presence and arrangement of the tabulating mechanism. Hence the printing roll and inking mechanism are below the table and the anvil or platen is above the table. The anvil or platen 42, see especially Figs. 1, 2 and 4, has a flat lower face and is secured to the forward ends of arms 44 that are carried by a reciprocating loop frame 46 having a horizontally elongated passage 48 therethrough for a web of paper, the frame being pivoted above the table on a horizontal shaft 50 carried by upstanding ears 52 of a bracket 54 secured to the underface of the table. Said bracket has depending ears 55 located beneath the table in which an oscillating shaft 56, see also Fig. 4, is journaled. Said shaft is oscillated by an operating lever 58 which is fixed to said shaft and has a pivotal connection with the upper end of a connecting rod 60, the lower end of the connecting rod being reciprocated by the continuously rotating shaft 62 of a power mechanism 64 well known in the art and not necessary to explain in greater detail. Said shaft is driven through meshing large and small gears 66 and 68 by a pulley 70 that is rotated by a motor 72. Rotation of the shaft 62 is under control of clutch mechanism operated by the treadle 74.

The operating lever 58, see especially Fig. 4, is provided with cam surfaces 76, 78 and 80 which cooperate with a cam roller 82 adjustably carried by the lower end of a depending arm 84 of the loop frame 46, the roller being held in constant engagement with the cam surfaces by a tension spring 86 connected with said arm 84. The arrangement is such that as said operating lever 58 is reciprocated vertically the loop frame and the platen are caused to be reciprocated to move the platen into and out of cooperative relation with the stencil sheet of the stencil.

The printing mechanism includes an ink-bearing printing roller 88 which is located beneath the stencil track and under the platen 42. Said roller is journaled on a shaft 90 that is carried by and is located between the upstanding forward ends of a pair of arms 92, the rear ends 75 of said arms being pivoted on a shaft 94 extended

between and carried by the ears 52 of the bracket 54. The operating lever 58 is provided with an upper horizontal part 96 that has a cam face 98 engaged by a cam roller 100 carried by said arms 92. The arrangement of the cam is such that as the operating lever 58 is reciprocated the arms 92 and the printing roll 88 are reciprocated vertically so as to move the printing roll into and out of pressure engagement with the stencil.

The inking mechanism for the printing roll is located below the table 30 and forwardly of the printing roll and is carried by a pair of brackets 102, see especially Figs. 3 and 4, secured to and depending below the table 30. The inking mechanism includes a drum 104 located between said brackets and fixed to a shaft 106 that is freely rotatable in said brackets. A transfer roll 108 is fixed to a shaft 110 that is journaled in boxes 112 that are slidable toward and away from the drum 104, the boxes being urged toward said drum by springs 114, thereby to maintain the transfer roll 108 in continuous rotatable engagement with the drum 104. The transfer roll is located between said drum and the printing roll 88 and is so arranged that when the printing roll 88 is in its low position it is in rotatable engagement with the transfer roll and is rotated thereby so that the surface of the printing roll receives a coating of ink. When the printing roll moves upwardly on a printing operation it moves out of contact with the transfer roll.

An ink spreading roll 116 is located in rotatable engagement with the drum 104 on the front side thereof. Said spreading roll is fixed to a shaft 118 that is rotatable and axially movable in bearing boxes 120, see especially Fig. 3, carried by and adjustable in said brackets 102 toward and away from the drum 104 so as to maintain said transfer roll in rolling engagement with the drum. The shaft 118 is reciprocated axially by a worm 122 fixed to the shaft 118 and meshing with a worm gear 124 journaled on a frame 126 that straddles the worm and is free for axial movement with the shaft. The worm gear 124 is eccentrically pivotally connected to one end of a connecting rod 128, the other end of which is pivoted at 130 to one of the brackets 102 so that as the worm gear is rotated the frame 126 and hence the worm 122 and the shaft 118 are caused to be reciprocated. An ink fountain or ink containing roll 132 is rotatably carried by forwardly extended arms 134 journaled on the shaft 106 of the drum 104. Said ink roll when desired is adapted to make rolling engagement with the transfer roll 116. A spring 136 is in engagement with said arms 134 and serves to maintain the ink roll normally out of engagement with the transfer roll. An arm 138 is associated with said arms 134 and ink roll and is terminated at the front of the machine and is adapted to be depressed to move the ink roll downwardly into rolling contact with the transfer roll so as to renew the ink supply to the printing roll 88 upon need.

The shaft 118 of the transfer roll is rotated continuously by means of a pulley 140 which is driven by a belt 142 of the spring coil type which passes around a pulley 144 fixed to a jack shaft 146, see especially Fig. 2. Said jack shaft is rotated by means of a pulley 148 that is fixed thereto and is engaged by a belt 150 similar to the belt 142 that passes around a pulley 152 fixed to the gear shaft 69 of the power mechanism 64.

The stencil pusher 38, see Figs. 1, 2 and 4, is reciprocated by a link 154 one end of which is pivoted to the pusher and the other end of which

is pivoted to the forwardly extended arm 156 having a hub 158 journalled on a vertical stud shaft 160 carried by and located beneath the table 30. The lower end of said hub is provided with a horizontally extended arm 162 terminated in a spherical end 164 located in a cam slot 166 of an operating segment 168, see also Fig. 3, which segment is carried by the shaft 56 and is connected with the operating lever 58 for conjoint reciprocation therewith. The shape of the cam slot 166 is such that the pusher is caused to advance a stencil by the width of the stencil at sometime during the period that the printing roll and platen are out of engagement with the 15 stencil.

The present invention is designed primarily to print the addresses of the stencils in succession transversely of a long paper web 170, see Figs. 2 and 4. Said paper web is contained in a roll 172 located at the rear of the table and rotatably supported by a shaft 174 journalled in brackets 176 projecting rearwardly from the edge of the table. The web 170 is passed forwardly and through the elongated passage 48 of the loop frame 46. Between the roll and the frame the web is slidably supported upon a table 178 having upstanding sides 180 spaced apart by approximately the distance of and disposed on opposite sides of the web. The table is transversely adjustably secured to the machine table 30 by means including the elongated slot 182 and the clamping nut 184, see Fig. 1, so that the web can be laterally positioned with respect to the printing roll, the platen and the tabulating mechanism presently to be described.

The web passes forwardly from the loop frame 46 into the bite of a pair of driven upper feed rolls 186 and lower idler feed rolls 188 located behind the rear edge of the stencil track. The upper 40 rolls 186, see Figs. 1, 2 and 4, are fixed to a shaft 190 that is journalled in bearings of a cross bar 192 secured to and upstanding above the top face of the table 30. The shaft and said rolls are intermittently advanced in the same direction 45 and at times are held stationary and thus serve to advance the web intermittently, the advance taking place during the time that the printing roll and platen are out of engagement with the web and stencil.

50 The lower rolls 188 are idler rolls and each, see Fig. 5, is separately journalled on a stud screw 194 carried by a yieldingly supported plate 196. Said plate is guided for vertical movement on vertical pins 198 carried by and rising from the bracket 54, there being helical springs 200 which encircle said pins beneath and bear upwardly against said plate 196, whereby to maintain said plate yieldingly in an elevated position and to hold said rolls 188 into engagement with the 55 paper web on the feed rolls 186.

At times, as for initially threading the web through the machine, it is desirable to move the lower or idle rolls downwardly and away from cooperative relation with the feed rolls. For this 60 purpose there is provided a release bar, see Figs. 3, 4, 5 and 6, which bar is essentially in the form of a crank and has an intermediate portion 202 journalled in the table of the machine and at right angles therewith and rearwardly extended 65 therefrom a rear end portion 204 that overlies the plate 196. Said end portion is so disposed that when it is depressed it engages said plate and moves said plate downwardly thereby carrying with it the idler rolls 188. Said rod has a 70 right angularly related forwardly extended por-

tion 206 that extends to the front of the machine and serves as a handle by which the rear end of the rod can be depressed. The handle end of the rod is somewhat resilient and is releasably retained resiliently in the lower notch 208 of a 5 depending holding plate 210, in which notch the rod is held in a normal inoperative position. The rod can be sprung sidewise out of the notch 208 and raised and sprung into the upper notch 212 of said plate whereby to hold the rod releasably in 10 an operated position with the idler rolls out of operative relation with said rolls.

The feed roll shaft 190 is provided with a pinion gear 214, see especially Figs. 1, 2 and 3, that is in mesh with a large gear 216 of the web feeding 15 mechanism. Said gear 216 is fixed to a shaft 218 journalled in a bracket 220 supported by the cross bar 192. The other end of said shaft has fixed thereto an integral brake drum 222 and ratchet wheel 224. The brake drum is engaged frictionally by a resiliently mounted brake shoe 226 carried by the cross bar 192 so as to hold the feed rolls and hence the paper web stationary when the rolls are not positively advanced by the ratchet wheel.

25 A pawl arm 228 is journalled on the end of said gear and ratchet wheel shaft 218 and at its free end carries a pawl 230 that engages the teeth of the ratchet wheel. An intermediate part of said pawl arm is intermittently connected to the lower 30 end of a connecting rod 232 which has a longitudinally elongated slot 234, see Fig. 2, therein into which projects a pin 236 of an upstanding arm 238 carried by the loop frame 46. A feed control rod 240 is screw-threaded into the end of said 35 connecting rod and has its end located in said slot in position to be engaged by the pin 236. A tension spring 242 is connected with said connecting rod and serves to urge it constantly downwards thereby to tend to maintain said pin 236 40 and rod 240 in engagement. Said loop frame 46 reciprocates during the printing operation and hence said pin 236 moves generally downwardly and upwardly. The downward movement of the pin is accomplished free from corresponding 45 movement of the connecting rod, the connecting rod moving under influence of the spring 242 to retrieve the pawl. During the upward movement of the loop frame, however, the pin 236 comes in contact with the end of the rod 240 and hence 50 raises the connecting rod and positively advances the feed rolls. The amount of upward stroke of the loop frame that is effective in positively advancing the feed rolls is regulated by the adjustment of the feed screw 240.

55 The paper web passes forwardly from the feed rolls and over and upon the stencil track and the stencils therein and under the platen and through the tabulating mechanism and thence over a guide bar 244, see Figs. 1, 2 and 4, to a 60 winding roll 246. Said winding roll is located at the front end of the machine and is carried on a shaft 248 journalled in a bracket 250 and preferably is releasably secured to the front part of the table 30. The shaft 248 is continuously 65 rotated by means of a pulley 252 fixed thereto and driven by a belt 254 that is passed about a pulley 256 fixed to the shaft 118 of the ink transfer roll. While the take-up drum 246 is thus continuously rotated the feed of the web is controlled by the feed rolls 186 and when said rolls are held stationary the take-up roll is held stationary and the drive thereof is adapted to slip. Thus the take-up roll operates only when paper 70 is advanced by the feed rolls.

- The tabulating mechanism that records the data indicated by the perforation of the stencil frame is located at the front part of the table 30 and in front of the printing roll and platen and 5 in line with the stencil that is in addressing position. The tabulating mechanism includes a supporting frame, see especially Figs. 4, 7 and 8, 9, comprising a horizontal bottom plate 258 carried by and resting in a recess formed in the 10 upper face of the table and removably secured thereto and having upstanding side bars 260 located at the opposite side edges of the plate and a cross bar 262 that rests upon the side bars 260 and is vertically spaced above the bottom plate. 15 The top and bottom plates and the side bars define a guide channel in which a plurality of printing devices 264 are located. Said printing devices are or can be identical and one is illustrated in perspective in Fig. 10.
- 20 Each of said printing devices comprises a horizontally thin bar that rests upright on its long narrow edge on top of the plate 264 and is horizontally movable on said plate under said top plate 262. All of the bars are in sidewise engagement with each other and the end bars of the 25 series are in sidewise engagement with the end bars 260. Each bar is provided intermediate its length with a raised part 266 having a series of raised type characters 268 in the form of numerals 30 thereon, the numerals running consecutively from zero to nine. The spacing between the numerals corresponds to the spacing between the horizontal lines of the tabulating form of the stencil and the spacing of the type characters 35 between any two consecutive type bars corresponding to the horizontal spacing of the numerals of the tabulating form and thereby to the spacing of the vertical lines of the form. Thus the entire set of type bars form a duplicate of 40 the tabulating form of the stencil.
- Each type bar at its inner or rear end is provided with a resilient upstanding spring finger 270 having an abrupt free end 272. The width of 45 the finger is such that it is free to enter a perforation of the stencil, which perforation preferably is rectangular and the abrupt free end of the finger is adapted to engage the rear end wall of the perforation and thereby be held from rearward movement. The finger also is of such configuration at its free end that it fits within 50 the perforation sufficiently so that the perforation holds it from deleterious forward or backward movement until the bar is positively moved forward by means independent of the stencil.
- 55 The arrangement is such that when the type bars are released for rearward movement toward the stencil they will move rearwardly until the spring fingers become seated in perforations aligned with the respective type bars, whereupon the type bars will be held from further movement. The position of the type characters on 60 the type bars is such that when a type bar is stopped from rearward movement by engagement of a spring finger with a perforation the type character on said type bar that corresponds with the numeral of the stencil cut out by the perforation will be located in position for printing.
- 65 The forward ends of all type bars are provided 70 with elevated stop projections 274 that are adapted to engage the front edge of the top guide plate 262 whereby to limit the rearward movement of the bars. The bars are biased for rearward movement towards the stencils by a spring 75 actuating mechanism consisting of a series of

upstanding thin levers 276 pivoted on a bar 278, see Figs. 3 and 4, disposed below the forward ends of the type bars and fixed to and extended between forwardly extending arms 280 carried by the brackets 102, there being interposed spacing 5 washers 282 on the bar 278 between the levers. The upper ends of the levers are loosely located in slots 284 formed in the front ends of the type bars. Tension springs 286 have their front ends connected with said levers and the rear ends of 10 alternate springs connected with alternate upper and lower projections 288 of a spring supporting bar 290 fixed to and extended between the brackets 102. Thus when the bars are released for rearward movement their respective springs 15 and levers urge each rearwardly until they are stopped from rearward movement by engagement of their respective fingers in the perforations of a stencil, as illustrated in Fig. 8 or by engagement of their stop projections 274 with the front 20 edge of the top plate 262.

The rearward movement of the type bars and their return to normal forward position is governed by a horizontally reciprocating frame, see Figs. 4, 8, 9 and 11. Said frame comprises a 25 plate 292 disposed beneath the plate 258 and horizontally slidable in the grooves of spaced rails 294 secured to the underface of said plate. Said plate 292 at its rear end is provided with an upstanding horizontal bar 296 that confronts the 30 inner or rear ends of but is free from positive connection with all of the type bars and hence when said bar 296 is moved rearwardly the type bars are free for rearward movement and when the bar 296 is moved forward it engages the rear ends 35 of all of the type bars and moves them positively forwardly against the action of their associated springs.

The plate 292 is secured to a bar 298 that at its forward end has a depending projection 300 40 formed with a vertical slot 302 therein. A pin 304, see Figs. 3, 4 and 8, is located loosely in said slot and is secured to the upper end of a generally vertical reciprocating lever 306 that at its lower end is pivoted on a stud pin 308 carried by a 45 depending bracket 310 attached to the underface of the table 30. The lower end of the lever 306 is integral with or fixed to a hub 312 that has a generally vertical arm 314 that at its free end carries a cam roller 316 engaged with a cam 318 50 which causes the arms 314 to reciprocate and hence effects the reciprocation of the control frame for the type bars. The cam 318 is fixed to a short shaft 320 journaled in the bracket 310 and having fixed thereto a sprocket 322, see Figs. 55 2, 3 and 12, that is driven by an endless chain 324 from the constantly driven shaft 62 of the power mechanism so that the shaft and cam rotate in timed relation with the movements of the stencil printing mechanism. The arrangement is such that the type bars are allowed to move forwardly and are retracted during the time that the stencil is stationary in printing position between the printing roll and platen.

A reciprocating printing head 326, see Figs. 1, 65 2, 3, 4 and 9, is located above the type bars and is vertically reciprocable in a supporting standard 328 fixed to a bridge 330 which overlies the type bars and has feet 332 that are secured to the table on opposite sides of the type bars. The 70 printing head carries at its lower end a platen 334 that has an impression ledge 336 that overlies all of the type bars and has a width sufficient to engage one type character only of all of the type characters of a type bar at one print- 75

ing operation. The printing head is urged for downward movement in a printing direction by a tension spring 338 and is elevated by a gear sector 340 that engages rack teeth 342 formed 5 in the printing head. The sector 340 is fixed to a shaft 344 journalled in the standard 328 and also in a bracket 346, see Fig. 1, rising from the top of the table and has a forwardly extended arm 348 fixed to its free end. The upper end of 10 a connecting rod 350 is pivotally connected to said arm, see Figs. 4 and 12, and the lower end of said connecting rod is pivoted to an intermediate part of a forwardly extended arm 352 that is loosely journalled on the shaft 56, see Fig. 3. 15 The forward end of said arm carries a cam roller 354 that bears upon a cam disc 356 secured to the shaft 320. The arrangement is such that for the greater part of a complete rotation of the shaft 320 the arm 352 and hence the printing head are held in an inactive elevated position but during a part of the rotation of the shaft the arm and printing head are allowed to drop down and effect the printing operation, this 20 operation taking place at the time the stencil is stationary.

The paper web 170 passes under the printing head and above the type bars. An ink ribbon 358 extends transversely of the type bars above them and under the paper web and the platen 334 and supplies the ink necessary for recording 25 the impression of the type characters of the type bars on the web. The ink ribbon is extended between rolls 360 and 362 carried by spindles 364 which are adapted to be rotated by hand to position new parts of the ribbon in printing position although automatic ribbon advancing mechanism of any type common in the art and not necessary herein to illustrate can be employed. The ribbon passes over a supporting table 366 that 30 is carried by the side bars 260 of the type bar supporting frame and has a cut-out portion 368 underlying the impression ledge 336 of the platen and exposing certain of the type characters of the type bars to receive the impression of the 35 printing head.

As thus arranged the address borne by a stencil when it is in printing position will be recorded upon the web 170. At the same time the type bars that are in line with perforations of the stencil will be stopped by the perforations in 40 position to present for printing type numbers that correspond with the numbers punched out by the perforations and these numbers will be recorded on the web in association with the address during the printing operation. Fig. 13 45 illustrates a portion of the printed web wherein the address 370 corresponds with the address 24 of the stencil of Fig. 14 and wherein the line of numbers 372 under the address 370 corresponds with the numbers, and with the horizontal position of the numbers, punched out by the 50 perforations 26 of Fig. 14.

I claim:

1. An addressing machine comprising means 55 for advancing a succession of address bearing devices to an addressing position, said devices having selectively positioned print-controlling means the position of which denotes a selected item of information, addressing mechanism operable upon 60 said devices in said printing position to record the addresses thereof, and printing mechanism having means for printing variable data directly controlled by the print-controlling means of the addressing devices for effecting the printing of 65 the items of information denoted by the posi-

tions of said print-controlling means upon the same record sheets with the addresses of the devices.

2. An addressing machine comprising means for advancing a succession of address bearing devices to an addressing position, said devices having printing data selecting means, addressing mechanism operable upon said devices in said printing position, and printing mechanism having means for printing variable data, arranged for 10 direct control by said data selecting means for printing the data selected by said printing data at the time the device is in addressing position and on the same record sheets with the addresses 15 of said devices.

3. An addressing machine comprising means for advancing a succession of address bearing devices to an addressing position, said devices having means denoting specific data, addressing mechanism operable upon said devices in said 20 printing position to record the addresses thereof, and printing mechanism having means directly responsive to said data denoting means of different address bearing devices to effect the printing of the specific data denoted by said data 25 denoting means upon the same record sheets with the addresses of said devices.

4. An addressing machine comprising means for advancing to an addressing position a succession of address bearing devices having in addition to the address printing-mechanism-controlling means located at selected parts of the device and capable of being differently located with different devices, each of said means denoting some data, addressing mechanism operable upon the 30 devices when they are in printing position to record the addresses thereof, printing mechanism having means for printing different data directly 35 responsive to the printing-mechanism-controlling means of the address bearing devices for printing the specific data that is denoted by said printing-mechanism-controlling means of the various 40 devices, data denoting means upon the same record sheets with the addresses of said devices.

5. An addressing machine having means to 45 advance into addressing position successive address bearing devices also bearing printing-mechanism-controlling means selectively positioned on said devices, and printing mechanism having means for printing different data under direct control of the printing-mechanism-controlling 50 means of said address bearing devices for printing the data corresponding to positions of said printing-mechanism-controlling means on a record sheet, and means for recording on the same 55 sheet the address of the printing device.

6. A printing machine comprising means for advancing into printing position a succession of printing devices having printing-mechanism-controlling abutments selectively positioned on said printing devices, printing mechanism having means for printing different data, means governing the printing of different data corresponding to different possible positions of said abutments on said printing devices, said means being movable over said printing devices into engagement with an abutment and being held thereby in a position wherein data corresponding to the position of the abutment is presented for printing, and means to effect a printing operation from the 60 printing data so presented.

7. An addressing machine comprising means for advancing into addressing position a succession of address bearing devices having data indicating devices, and means directly operative 70 75

upon the devices when they are in addressing position for making a record both of the address and the data indicated by a device on the same record sheet.

- 5 8. Addressing mechanism comprising means for advancing into printing position a succession of address bearing devices having selectively positioned printing data indicating members, variable data printing mechanism having a plurality of data controlling members the position of which determines the data that is printed, the position of said members being determined by the position of said indicating members, and means for recording at the same time while the devices 10 are in printing position the address of an address bearing device and the data determined by said indicating members, said recording means including addressing mechanism operable to record the impression of the address of the device when it is 15 in printing position.

9. An addressing machine comprising means for advancing into addressing position a succession of address bearing devices having selectively positioned printing data indicating members, 20 addressing mechanism for recording the addresses of said devices, a printing mechanism adapted to print different data as determined by the position of said indicating members, a plurality of data controlling members the position of which determines the data printed by said printing mechanism, said members being aligned with said indicating members when the addressing device is in addressing position, means for moving said data controlling members into abutting and holding 25 relation with said indicating members, whereby to present for printing data denoted by the position of said indicating members, and means for recording the data presented by said printing mechanism and as determined by said indicating members.

- 40 10. In a printing machine, the combination of means for advancing into printing position a succession of devices having selectively positioned printing data indicating members, printing mechanism having a plurality of movable printing 45 data carrying members each having a plurality of printing data thereon, said movable members being positioned in alignment with said indicating members when an addressing device is in printing position, and means for moving said movable members into engagement with said indicating members whereby to be positioned thereby in positions to present data corresponding to that of said indicating members.

- 55 11. An addressing machine comprising means for advancing into addressing position a succession of address bearing devices having selectively positioned type indicating members, addressing mechanism for recording the addresses of said devices, printing mechanism having a plurality of movable type carrying bars, each bar carrying a plurality of different type characters, said type bars being positioned in alignment with said indicating members when an addressing device is in addressing position, means for biasing 60 said type bars for movement towards an addressing device when it is in addressing position, means for effecting engagement of the aligned type bars with said indicating members and for holding said type bars in positions corresponding to the positions of said indicating members, means for recording the type characters presented by the positioned type bars, and means for returning said type bars to a normal 65 position.

12. An addressing machine comprising means for advancing into addressing position a succession of address bearing devices having selectively positioned type indicating members, addressing mechanism for recording the addresses of said devices, printing mechanism having a plurality of type carrying bars disposed in alignment with said indicating members when an addressing device is in addressing position, said type carrying members each having a plurality of different type characters, means for biasing said type bars for movement toward said addressing devices, means carried by said type bars engageable with said indicating members and operable to hold said type bars in positions corresponding to the 10 positions of said indicating members, means for recording the type characters presented by the positioned type bars, and means for returning said type bars to a normal position.

13. An addressing machine comprising means 20 for advancing into printing position a succession of address bearing stencils having selectively positioned type indicating perforations, addressing mechanism for recording the addresses of said stencils, printing mechanism having a plurality 25 of type bars aligned with perforations of a stencil when the latter is in addressing position, said type bars each having a plurality of different type characters, means for biasing said type bars for movement toward the stencil, spring fingers 30 carried by said type bars movable therewith upon the surface of said stencil and into a perforation aligned therewith held thereby against further movement in an advancing direction 35 whereby to position for printing that type character of the type bar that corresponds with the printing character indicated by the perforation, means for recording the character presented by the positioned type bar, and means for returning said type bars to a normal position.

40 14. In an addressing machine, the combination of means for advancing into printing position a succession of address bearing devices having selectively positioned type indicating members, printing mechanism including a platen, a plurality of type bars movable toward and away from said addressing position and under said platen, each type bar having a plurality of different type characters, means for biasing said type bars for movement towards the addressing position comprising a supporting shaft, a plurality of arms pivoted on said shaft each engageable with a separate type bar, spring means acting on said arms for biasing them and said type bars for movement into engagement with said indicating members, and means for controlling said movement and for returning said type bar to a normal position.

45 15. A printing machine comprising means for advancing into printing position a series of devices having selectively positioned type indicating members, printing mechanism having a plurality of type bars movable into engagement with said indicating members when a device is in printing position, said type bars each having a plurality 50 of different type characters, means biasing said type bars for movement towards said devices, and means for controlling said movement and for returning said bars to normal position.

60 16. In an addressing machine, the combination 70 of means for advancing into addressing position successive address bearing devices having selectively positioned type indicating members, addressing mechanism for recording the addresses of said devices, printing mechanism having a plu- 75

- 5 rality of movable type bars each having a plurality of different type characters, spring means for biasing said type bars for movement into engagement with the indicating members of an address bearing device when the latter is in addressing position, means for holding said type bars against movement and for permitting independent movement of said type bars into engagement with said indicating members and for returning all of said members simultaneously into a normal position, and means for recording the characters presented by the positioned type bars.
- 10 17. In an addressing machine, the combination of means for advancing into printing position a succession of address bearing devices having selectively positioned type indicating members, printing mechanism having a plurality of type bars each having a plurality of different type characters, means for biasing said type bars for movement into engagement with said indicating members, and a reciprocating frame engageable with said type bars for releasing said type bars for independent movement and for returning said type bars simultaneously into a normal position.
- 15 18. In an addressing machine, the combination of means for advancing into printing position a succession of address bearing devices having selectively positioned type indicating members, printing mechanism having a plurality of type bars each having a plurality of different type characters, means for biasing said type bars for movement into engagement with said indicating members, a reciprocating frame engageable with said type bars for releasing said type bars for independent movement and for returning said type bars simultaneously into a normal position, and means for recording the address of an address bearing device and impressions of the type bars as determined by the settings thereof.
- 20 19. In a printing machine, the combination of means for advancing into printing position a succession of devices having selectively positioned type indicating members, printing mechanism comprising a supporting plate, a plurality of movable type bars positioned in sidewise engagement upon said plate, means for biasing said type bars for lengthwise movement over said devices into direct engagement with said indicating members, and a reciprocating frame controlling the movement of said type bars and returning said type bars to a normal position.
- 25 20. An addressing machine comprising the combination of a track, means for advancing along said track into a printing position a succession of address bearing stencils having selectively positioned type indicating perforations, printing mechanism located at one side of said track having a plurality of type bars each having a plurality of different type characters, means for biasing said type bars for movement lengthwise toward and away from and under said track, said type bars having spring urged fingers which are movable over and in pressure engagement with a face of a stencil when it is in printing position and into a perforation registering therewith whereby to hold its type bar against further advancing movement and to position into printing position a type character thereof that corresponds with the type indicated by the associated perforation, a reciprocating frame engageable with all of said type bars and returning them into a normal position.
- 30 21. An addressing machine comprising a guideway, means for advancing into addressing position along said guideway a succession of address bearing devices having type indicating members, a printing mechanism located beside said guideway having a plurality of type carrying members, means directly controlled by said indicating members for locating said type carrying members in positions for presenting in a printing position type characters of said type carrying members corresponding to the type indicated by said indicating members, means for advancing a record sheet into printing relation with the address bearing devices and also with the type characters of said printing mechanism, and means for recording in cooperative association upon said record sheet the address of a device and the type characters selected by the indicating members of the device.
- 35 22. In an addressing machine, means for advancing into printing position a succession of address bearing devices having address characters forming a readable address and also selectively positioned type indicating members, printing mechanism including a plurality of movable printing devices each having type characters, means under control of and having parts directly engageable with said indicating members for assembling said printing devices in a predetermined position determined by the position of said indicating members, and means for directly recording an impression of the address characters of an address bearing device and the impression of said selectively assembled type characters of said printing devices.
- 40 23. A printing machine comprising a plurality of movable type bars each having a plurality of different type characters, means for advancing a plurality of control devices having selectively positioned type character selector members into controlling position with said type bars, means for moving said type bars into abutting relation with said selector members whereby to present into a printing position type characters of said type bars corresponding to type characters indicated by said selector members, means for making a record of said selected type characters, and means for returning said type bars to a normal position.
- 45 24. A printing machine comprising means to advance a succession of control devices into a control position, each device having a tabulating form composed of a series of horizontal lines of numbers, each line having repetitions of the same number and each line having representation of a different number, the numbers of the horizontal lines being contained in vertical lines, printing mechanism comprising a plurality of bars, there being as many bars as there are vertical lines of the control devices, each bar having associated therewith a plurality of type characters corresponding to the type characters of horizontal lines contained in the associated vertical lines of the control device, said bars being movable into successive positions corresponding with the positions of the associated type characters in printing position, the control devices having control members positioned in selected horizontal and vertical lines, and means operable to move said bars into abutting relation with said control members whereby to position into printing position the type character associated with a bar and corresponding to the type character position of the control member, and means for making a record of the positioned type characters.
- 50 25. A printing machine comprising means to

- advance a succession of control devices into a control position, each device having a tabulating form composed of a series of horizontal lines of numbers, each line having repetitions of the same number and each line having representation of a different number, the numbers of the horizontal lines being contained in vertical lines, printing mechanism comprising a plurality of bars, there being as many bars as there are vertical lines of the control devices, each bar having associated therewith a plurality of type characters corresponding to the type characters of horizontal lines contained in the associated vertical lines of the control device, said bars being movable into successive positions corresponding with the positions of the associated type characters in printing position, the control devices having control members positioned in selected horizontal and vertical lines, and means operable to move said bars into abutting relation with said control members whereby to position into printing position the type character associated with a bar and corresponding to the type character position of the control member, means for making a record of the positioned type characters, and means for returning all type bars and associated type characters into a normal position.
26. In a printing machine the combination of a printing head, a plate located beneath said head, a plurality of type bars disposed upon said plate in parallel sidewise arrangement, means overlying said bars and engaged slidably thereby while retaining said bars in the aforesaid relation, said bars having a plurality of type characters distributed lengthwise thereof, spring means for biasing each of said bars independently of all other bars for lengthwise movement in one direction, means including a reciprocating frame common to all bars for holding said bars against such movement and for releasing said bars for independent movement and for returning said bars to a normal position, means for operating said printing head when said bars are in displaced positions and a changeable control plate traversed by parts of said bars and having means engageable therewith for holding said bars in predetermined displaced positions during the operation of said printing head.
27. Addressing mechanism comprising a guideway, means for advancing along said guideway into printing position a succession of address bearing devices having address forming characters and changeable printing data indicating means, means for locating a record sheet in printing position, addressing mechanism for recording the impression of the address forming characters of an address bearing device on said record sheet, printing mechanism having changeable printing data directly controlled by said printing data indicating means for selecting the data to be printed, and means for recording the selected data upon the face of said record sheet bearing the address.
28. Addressing mechanism comprising a guideway, means for advancing along said guideway into printing position a succession of address bearing devices having address forming characters and changeable printing data indicating means, means for locating a record sheet in printing position, addressing mechanism for recording the impression of the address forming characters of an address bearing device on said record sheet, printing mechanism having changeable printing data directly controlled by said printing data indicating means for selecting the data to be
- printed, and means for recording the selected data upon the face of said record sheet bearing the address, said address bearing device comprising a stencil, said addressing mechanism comprising a reciprocable printing platen located above the stencil and guideway, and a printing roll located below said stencil and guideway, said record sheet being disposed above the stencil and guideway, said changeable printing data means being located beneath said record sheet and printing upon the under face thereof, and inking mechanism for said printing roll disposed below said guideway.
29. In an addressing machine, the combination of means for advancing into printing position a succession of address bearing devices having selectively positioned control perforations, a plurality of separately movable printing members advanceable over an address bearing device when the latter is in a predetermined location and having projections adapted to enter a perforation registering therewith and be held by the device from continued movement in the same direction, means for advancing said members in the aforesaid manner, means for retracting said members from advanced positions thereof, and means for effecting a printing operation on said members when they are in predetermined advanced positions.
30. Printing mechanism comprising a table, a guideway above said table, printing mechanism including a printing arm pivotally carried by said table above and at the rear part thereof and extended forwardly, a platen carried by the forward end of said arm and overlying said guideway, means for advancing successive printing devices along said guideway and under said platen, a roll carrying frame pivotally carried by said table below and at the rear part thereof and extended forwardly, a printing roll carried by the forward part of said frame, means for reciprocating said arm and frame about their pivotal connections with said table for moving said platen and printing roll respectively downwardly and upwardly into printing relation with said printing devices in said guideway, said means including a shaft located below said guideway and table, and cam mechanism on said shaft extended rearwardly therefrom and having operative connections with said arm and roll carrying frame below said table, and inking mechanism for said printing roll located below said guideway and table and forwardly of said roll and shaft.
31. A printing machine comprising means for advancing into and out of a printing position a succession of printing devices bearing addresses and selectively positioned item indicating means, means for recording the address of a printing device, and means directly controlled by said item indicating means for recording on the same sheet with the address a record corresponding to said item indicating means.
32. The combination of an address plate having address characters and data denoting means occupying different positions on said plate denoting different data, means for recording the address on a record sheet, and means under direct control of said data denoting means for recording on the same sheet with the address a mark for each data denoting means which marks are indicative of the positions of said data denoting means.
33. The combination of a printing plate having address characters and means the positions of which on said card indicate different data, means for recording the address of said card, and means cooperating directly with said first-named means

for recording on the same record sheet with the address the positions of said data indicating means.

34. An addressing machine having address printing mechanism and other printing devices in combination with a printing plate having address printing characters and holes controlling the operation of the printing devices, the holes being

registerable with parts of printing devices which are selected by the positions of such holes and the printing device parts being movable into said holes to condition the printing devices for printing data corresponding to the position of said holes. 5

HARMON P. ELLIOTT.
